(57) **CLAIM**

The ornamental design for a bottle opener, as shown and described.

DESCRIPTION

FIG. 1 is a first, front perspective view of a bottle opener, in a first embodiment, showing my new design;

FIG. 2 is a front elevation view of the bottle opener of FIG. 1;

FIG. 3 is a right side elevation view of the bottle opener of FIG. 1;

FIG. 4 is a rear elevation view of the bottle opener of FIG. 1;

FIG. 5 is a left side elevation view of the bottle opener of FIG. 1;

FIG. 6 is a top plan view of the bottle opener of FIG. 1;

FIG. 7 is a rear perspective view of the bottle opener of FIG. 1;

FIG. 8 is a bottom plan view of the bottle opener of FIG. 1;

FIG. 9 is a second front perspective view of the bottle opener of FIG. 1;

FIG. 10 is a first, front perspective view of the bottle opener, in a second embodiment, showing my new design;

FIG. 11 is a front elevation view of the bottle opener of FIG. 10;

FIG. 12 is a right side elevation view of the bottle opener of FIG. 10;

FIG. 13 is a rear elevation view of the bottle opener of FIG. 10;

FIG. 14 is a left side elevation view of the bottle opener of FIG. 10;

FIG. 15 is a top plan view of the bottle opener of FIG. 10;

FIG. 16 is a rear perspective view of the bottle opener of FIG. 10;

FIG. 17 is a bottom plan view of the bottle opener of FIG. 10;

FIG. 18 is a second front perspective view of the bottle opener of FIG. 10;

FIG. 19 is a first, front perspective view of the bottle opener, in a third embodiment, showing my new design;

FIG. 20 is a front elevation view of the bottle opener of FIG. 19;

FIG. 21 is a right side elevation view of the bottle opener of FIG. 19;

FIG. 22 is a rear elevation view of the bottle opener of FIG. 19;

FIG. 23 is a left side elevation view of the bottle opener of FIG. 19;

FIG. 24 is a top plan view of the bottle opener of FIG. 19;

FIG. 25 is a rear perspective view of the bottle opener of FIG. 19;

(Continued)

FIG. 26 is a bottom plan view of the bottle opener of FIG. 19; and,

FIG. 27 is a second front perspective view of the bottle opener of FIG. 19.

The broken lines shown in the drawings depict portions of the bottle opener that form no part of the claimed design.
